A. L. Jackson.
ATTORNEY.

UNITED STATES PATENT OFFICE.

JOHN GRAHAM, OF FORT WORTH, TEXAS.

FROGLESS SWITCH.

SPECIFICATION forming part of Letters Patent No. 618,411, dated January 31, 1899.

Application filed May 31, 1898. Serial No. 682,117. (No model.)

To all whom it may concern:

Be it known that I, JOHN GRAHAM, a citizen of the United States, residing at Fort Worth, Texas, have invented certain new and useful 5 Improvements in Frogless Switches, of which the following is a specification.

My invention relates to an improved railway-way-switch which can be adapted for use on any-gage railroad; and the invention consists 10 in improvements for operating a switch without the use of frogs and guard-rails, and the object is to construct a switch which is simple in construction and easily operated and which is strong and durable and not expensive 15 to manufacture. By dispensing with frogs and guard-rails the danger of losing lives is lessened, because there are no places in which the feet of switchmen can be caught. Another advantage in my switch is that there 20 is no jar to rolling-stock in passing over the switch or no more jar than on the ordinary track, and consequently no reduction of speed is necessary in passing over the switch.

My switch can be manufactured at a cost 25 of about seventy-five per cent. less than frogs and guard-rails.

Other objects and advantages will be fully described in the following description and particularly pointed out in the claim.

30 Reference is had to the accompanying drawings, forming a part of this application, Figure I being a section of a railway-track, showing my improved switch applied and a part of the rod for operating the switch. Fig. II is another section of a railway-track, being a continuation of the track shown in Fig. I and showing means for operating the switch. Fig. III is an enlarged view of the double-pointed pivoted swinging rail. Fig. IV is an enlarged 35 view of one side of the clasp for guiding the throw-slide.

Similar characters of reference are used to indicate the same parts throughout the several views.

40 In the drawings the main track is indicated by the figures 1 and 2, and the rail leading from the switch-point 3 is indicated by 2'. A side track having rails 4 and 5 is shown along with the main line. The side track is provided with a lead 6 and a switch-point 7. I use two head-chairs 8 and 9, which are at- 45 tached to ties 8' and 9', respectively. A swinging rail 10, about six feet long, having a point on each end about two and one-half inches long, is pivoted between the head-chairs 55 at its middle point on a plate 11. This swinging rail and its attachments take the place of the frog in other switches. The rail 10 is held in place by two spikes 12 and 13 and braces 14 and 15, which are attached to the 60 tie 15', spikes being driven through the plate 11. Braces 16 and 17 and 16' and 17' are attached to the castings of the head-chairs to prevent the possibility of the overlapping of the swinging rail 10. There is not much dan- 65 ger of this being done without these braces, because the points of the swinging rail lap against the rails 2, 2', 6, and 5. The points of this rail move from side to side on cut-outs 18 and 19 in the head-chairs 8 and 9. All the 70 braces have cut-outs for the flange of the rails and none of the braces are high enough to be struck by the flanges of the car-wheels, the inner edges of the braces coming in the necks of the rails. The swinging rail 10 is 75 operated by the rod 20, which is about eighty feet from the point of attachment to rail 10 to the bridle-rod 21 of the throw-stand. This rod is provided with guides 22, attached to the ties about twenty feet apart. There is 80 an offset at 23 in order to go under the point 3 and another offset at 24 to bring the rod up to be on a level with the cog-wheel 25 and cog-wheel 26. Near the center of the rod 20 is placed an adjusting-bolt 27 for regulating the length of the rod to conform to expansion and contraction of the track. This bolt is about six inches and has a swivel connection 28 at one end, and the rod has a threaded portion 29 to receive the other end 85 of the bolt. The rod 20 has a ratchet 30 on each side near the end to engage the cogs 25 and 26. It is preferable to have cog 26 eight inches in diameter and the cog 25 four inches in diameter. The cog 25 is a guard and a 90 support for the rod 20. With cog 25 on bolt-shaft 31 the switch will throw to the right, looking to the left of the sheet. If placed on the bolt-shafts 32, the switch will throw to the left. The bolt-shafts 31, 32, and 33 are about 95 seven-eighths of an inch in diameter. The bridle-rod 21 is provided with teeth 34, which

engage cog 26 when operated from the throw-
stand 35. The bridle-rod 21 and the throw-
stand 35 are the same as those used on all
switches, except that the bridle-rod has teeth
5 or a ratchet for engaging the cog-wheel 26.
Two clasps 36 hold the cog 26 and the bridle-
rod ratchet in mesh. A bolt 37, about five-
eighths of an inch in diameter, provided with a
suitable nut, holds these clasps on the bridle-
rod 21. The holes in the clasps 36 for the bolt
10 are elongated, so that there will be enough
play to prevent the binding of cog 26 and the
ratchet of the bridle-rod. The shaft-bolts 31,
15 32, and 33 are attached to a plate 38, which is
spiked to a tie. The throw, with the bridle-
rod, operates the points 3 and 7, and the
ratchet 34, with cogs 25 and 26, operates the
rod 20, and rod 20 operates the swinging rail
10 to adjust the points of said rail whenever
20 the points 3 and 7 are moved. The dotted out-
line shows how this rail is turned to connect
lead 2' with rail 2 to form a continuous track
for the main line and to connect the lead 6 to
rail 5 to form a continuous track for the side
25 track. The rod 20 may pass under the lead 2'
at any suitable place instead of passing under
the point 3. The guides 22 are simply to pre-
vent the rod 20 from being thrown out of place
when being operated. This rod has only a
30 longitudinal movement, except at the end
which is attached to the rail 10. The longi-

tudinal movement will cause the rod to spring
enough to operate the rail 10.

It will be observed that there are no guard-
rails and no frogs seen in most railroad- 35
switches.

Having fully described my invention, what
I claim as new, and desire to secure by Letters
Patent, is—

In a railway-track and side track provided 40
with suitable points and leads; the combina-
tion of a bridle-rod for throwing said points
and means for forming continuous tracks
from said leads to the rails of said tracks al-
ternatively, said means consisting of a dou- 45
ble-pointed swinging rail pivoted between
said leads and said rails, a rod for operating
said pivoted rail, said rod having ratchet-
teeth on each side near and extending to the
end thereof, two cog-wheels adapted to en- 50
gage said ratchet-teeth, said bridle-rod hav-
ing ratchet-teeth engaging one of said cog-
wheels, and clasps to hold said cog and said
ratchet in mesh.

In testimony whereof I set my hand, in the 55
presence of two witnesses, this 25th day of
May, 1898.

JOHN GRAHAM.
